ELECTRICAL APPLIANCE FOR CONTROLLING AIR-BRAKES

No. 888,648.

Specification of Letters Patent.

Patented May 26, 1908.

Application filed November 16, 1906, Serial No. 343,759. Renewed September 25, 1907. Serial No. 334,581.

To all whom it may concern:

Be it known that we, JAMES G. PEARCE and WILLIAM H. PEARCE, citizens of the United States, residing in Oakland, in the county of Alameda and State of California, have invented new and useful Improvements in Electrical Appliances and Circuits for Controlling the Air-Brakes on Railway-Trains in Motion, of which the following is a specification.

In the running and handling of railway trains at the present time accidents frequently happen that could well have been avoided if the brakes could be put on automatically and always at the proper moment to bring the train to a standstill at a safe distance from the danger-point, without depending on the judgment or the prompt action of the engineer. To effect such desired automatic setting of the air-brakes on a train in motion, and to control such operation from or by the relative position of the moving train with regard to other trains on the road, is the principal end and object of our invention.

To such end and object, mainly, our invention comprises an electrically actuated brake-controlling valve of novel construction as auxiliary to, or in addition to, the well known engineer's valve on the locomotive-engine, and a system of circuit-forming conductors and contact-blocks or projections on the roadway, in combination with the track-rails and with a local battery or source of current on the train.

The invention embraces further, a novel combination and arrangement of stationary, electrical conductors; fixed contact-blocks, or projections; and track-rails in separate blocks or sections for co-operating with a local circuit on the locomotive engine, in which is included the battery and the electrically-actuated brake-controlling valve; and a circuit-closing shoe or device on the engine for connecting the local circuit or closing it through the stationary conductors on the roadway; the track-rails and contact-blocks of the sections into which the road or line is divided being interconnected and cross-connected in a novel manner, whereby the wheels of a train either traveling or standing on any section will operate to electrically connect the track-rails and the contacts in the sections next ahead and behind, so as to form thereof in each section a continuous conductor having

for one of its sides the track-rail, and for the other the contact-blocks on the surface of the road.

The nature of our said invention, and the manner in which we proceed to produce, apply and carry out the same are explained at length in the following description, in which the accompanying drawings are referred to by figures and letters.

Figure 1 of the drawings is a side-elevation, partly diagrammatic, of our novel brake-controlling valve in the air-brake system, the local circuit through which it is operated, and the contact-shoe on the locomotive engine. Fig. 2 is a front-elevation of the frame and truck of the engine represented in Fig. 1, with the cow-catcher omitted. The contact-shoe and the fixed contact-block on the surface of the roadway is seen in this view. Fig. 3 is a diagram, showing the manner of connecting and arranging the track-rails and conductors in separate blocks, or sections, along a line of road, to set up and complete an electric circuit through the battery on the engine and the valve-actuating means, when the engine in its travel is entering a block or section that adjoins a block or a section already occupied by a train. Fig. 4 is an elevation, on an enlarged scale, of our novel brake-controlling valve detached from the train-pipe, and the connections between the supply-tank on the engine and the engineer's valve. Fig. 5 is a longitudinal sectional view taken on the line $x-x$, Fig. 4. Fig. 6 is a horizontal cross-section through $y-y$, Fig. 4. Figs. 7 and 8 are diagrams illustrating our system of stationary conductors and contact-blocks of a block or section of road that includes a switch or siding; Fig. 7 showing the portion of the block where the switch branches off, and Fig. 8, the continuation of the main line beyond the switch. Fig. 9 is a diagram representing our system of stationary conductors and contact-blocks at a crossing where one road crosses another at right angles.

In carrying out our invention the valve d —which may be termed the auxiliary valve—is connected with the compressed-air supply between the engineer's valve e and the pipe 1 running out of the train-pipe. Through the valve d communication between the train-pipe and the atmosphere is set up separately and independently of the engineer's valve by raising an outlet-valve 70 off its seat, and

thereby setting the brakes of the train. The lower end of the valve-stem 71 rests on the armature 72 of the magnet *h*, and as often as the current is passed through the coils of the magnet the valve 70 is lifted and the outlet is opened.

The coils of the magnet *h* are connected at one end into one pole of the local battery *w*, and the opposite pole into a contact-shoe *a* on the arm *b* carried by the engine. The remaining pole of the battery *w* is connected with one of the axles or trucks of the engine which is in electrical circuit with the engine wheels so as to carry or continue the circuit from that side of the battery directly to the rails on which the wheels may be traveling or resting. The shoe *a* and the truck and the wheels of the engine thus form the terminals of the local circuit that includes the battery *w* and the coils of the magnet *h*. But while it is standing open or broken under ordinary conditions, this circuit will be completed and the magnet will act on the valve-stem 71 whenever the rails in the block or section in front of the block on which the engine is traveling are connected together metallically, as by the wheels of another engine or train in the block. Under such conditions the conductors and rails in the block being entered and the rails in the block already occupied go to form a complete metallic circuit through the battery and the brake-actuating mechanism connected into the battery, at the moment that the contact-shoe *a* touches one of the contact-blocks on the surface of the roadway.

The diagram Fig. 3 illustrates the manner in which the rails and series of contact-blocks of any number of blocks or sections composing a line of road are cross-connected and inter-connected according to our invention, to operate our brake-controlling valve. The diagram represents four blocks or sections in which the rails are electrically isolated by placing insulation *x* between the ends of the rails. The remaining blocks will be but repetition of the manner of wiring or connecting the rails and the contact-blocks which we have shown in the diagram, with the exception of blocks that contain switches, sidings, or crossings. In such applications our plan of cross-connecting and interconnecting the rails and contact blocks will be slightly modified as represented in the remaining diagrams.

The rails of the different blocks or sections included in the diagram Fig. 3 are indicated at $m-m^1$, m^2-m^3 , m^4-m^5 and m^6-m^7 . The series of contact-blocks are seen at c^x-c^x , c^2-c^3 , c^4-c^5 , and c^6-c^7 . A conductor 5 connects the rail m^2 with the rail m^1 of the block next behind, but on the opposite side of the track; and a conductor 6 similarly connects the rail m^4 of the block ahead with the rail m^3 . In that block composed of the rails m^4-m^5 the rail m^5 is connected with the rail

m^6 of the next block by the conductor 7, and so on throughout all the remaining blocks.

The contact-blocks on the surface of the road are preferably placed between the rails. Those c^2-c^3 in the block composed of the rails m^2-m^3 are arranged in two sets or series placed at intervals apart and connected by the conductors n^1-n^2 ; the series n^3 being connected into the rail m of the block behind by the conductor 8, and the series c^3 with the rail m^3 of the block ahead by the conductor 11.

According to this plan one of the rails in each and every block or section is always in electrical connection with a series of contact-blocks in the section next ahead, and the other into a series of contact-blocks in the section next behind, as, for example, the rail m^3 with the contact-blocks c^4 in the section next behind.

In every block or section, therefore, the rails are employed to form conductors for a metallic circuit that contains or includes a series of contact-blocks in the section next behind, and a similar series in the section ahead, and also one of the rails in each of the before-mentioned sections.

The effect of interconnecting and cross-connecting the rails and contact-blocks of the sections in this manner is to set up or form a loop for a metallic circuit, of which the open ends or terminals will be composed of a rail and any one of the series of contact-blocks in the section, when the two sides or members of the loop are closed or connected in the section behind or the section ahead by the wheels of a train in either section, whether it be traveling or standing still. A loop thus formed on the roadway is completed and a metallic circuit closed through the battery on the engine at the moment that the contact-shoe *a* touches one of the contact-blocks composing one of the loop-terminals, and the valve *d* will be operated by the current passing over the circuit thus completed. On the other hand, there will be no current as long as the conductors that go to form the loop are not connected mechanically by the wheels of a train in the section ahead or behind. No circuit can be set up, and the brake-controlling valve *d* will not be operated as long as those sections are clear. The circuit thus completed through the battery and brake-operating means on the engine at the moment of entering on a section of the line when there is another train occupying the section ahead will be understood by tracing the circuit indicated in Fig. 3 by the arrows; the position of the two trains being represented by the dotted lines indicating a pair of wheels and an axle in each section.

As the wheels and the truck of the engine traveling or resting on the rails m^4-m^5 will obviously connect those rails together electrically, the loop which is composed of the rails m^4-m^5 , the rail m^3 and the contact-

blocks c^3 will be closed as long as the truck is traveling in the section m^4-m^5 , and the terminals of the loop will be found in the section m^2-m^3 . Under those conditions the local 5 circuit on the engine of a train entering the last-mentioned section will be closed at the moment that its contact-shoe touches one of the contact-blocks c^3 ; and the current from the battery w will pass from one pole out 10 through the wheels to the rail m^3 , thence over the conductor formed of the rails m^3-m^4 , and to the opposite rail m^5 , and back through the connection 11 to the series of contact-blocks c^3 , and finally to the other pole of the 15 battery; thereby completing the circuit through the coils of the magnet h . Similar conditions will also be found to exist in the block composed of the rails m^6-m^7 , in which the rail m^6 and the contact-blocks c^6 are in 20 metallic connection with the rails m^4-m^5 .

The diagrams 7 and 8 illustrate one application of our invention to the blocks or sections adjacent to, and at a switch or siding. In this arrangement the rails of the blocks or 25 sections on the main line are interconnected in the same manner as in the diagram Fig. 3; as, for example, the rail m^6 into the contact-blocks c^6 , the rail m^8 into the contact-blocks c^8 , and so on. But instead of employing the 30 contact-blocks for elements of circuits in the siding, we simply interconnect the rails of the latter and the rails of the main line. Thus the rail s is connected into the rail m^9 of the block m^8-m^9 by the conductor 20, and the 35 rail s^4 into the rail m^{13} and also into the rail m^{16} of the block $m^{16}-m^{17}$ by the conductors 23 and 24. These loop-forming members are also connected into a circuit-closing means in the switch-stands $p-p^1$, and each composed 40 of a rotatable circuit-closer and a series of fixed contacts around it.

The contacts 17-19 in the stand p are the terminals, respectively, of the conductor 16 running from the conductor 20 to the contact 45 17, and the conductor 18 from the conductor n^9 of the contact-blocks c^7 . The contact 15, situated between the contacts 17-19, is connected into the conductor n^{10} of the series of contact-blocks c^8 . Through this means the 50 formation of the metallic circuit is controlled in such manner that, if the switch be open the rail m^8 and the series of contact-blocks c^7 will be connected together through the circuit-closer on the switch-stand p , in which 55 the contacts 15-19 will be connected together. Or, at the opposite end of the switch, in the switch-stand p^1 the contacts 27 and 31 will be connected. The loop formed at such time will be composed of the rail m^{16} 60 conductors 24-28, contacts 27-31, conductor 30, the contact blocks c^{10} and conductors n^{14} . Through this circuit, as the train enters the block m^8-m^9 in approaching the switch from that direction, or as it enters 65 the block $m^{17}-m^{18}$ in approaching from the

opposite direction the magnet h will receive current from the battery w at the moment that the contact-shoe on the engine touches one of the contact-blocks, provided the switch is standing open. On the other hand, 70 with the switch properly closed, no circuit will be formed.

In the foregoing arrangement provision is made for automatically setting the brakes of a train running on the main track before it 75 approaches in too close proximity to the switch or side-track, in the event of a train being left standing on the siding in such position that the rear car might be struck by the moving train. Under such conditions the 80 wheels of the train standing on the siding will connect electrically the two rails s^4-s^5 , and so close or complete a circuit through the conductors and rails s^5-25-n^{14} , and contact-blocks c^{10} , and the rails and conductors 85 $s^4-23-24$ and m^{16} . The magnet h therefore will receive current from the battery w at the moment that the contact-shoe a indicated by the dotted lines in Fig. 8 on the main track touches one of the contact-blocks 90 c^{10} , if the rails s^4 and s^5 in the siding are connected through the wheels of the train standing on the siding.

The same plan of interconnecting and cross-connecting the series of contact-blocks 95 and rails in the blocks or sections on opposite sides of a crossing-point with another road will serve to prevent accidents at a crossing. In such application of our invention the contact-blocks and the rails in the 100 block on one side of the crossing are connected into the rails and the contact-blocks of the corresponding block or section on the opposite side; as, for example, the rail m^{20} in the diagram Fig. 9 is connected into the contacts on the surface of the block on the opposite side by the conductor 39^a; and the contact-blocks c^{15} into one of the rails of the last-mentioned block by the conductor 39, in the 105 same manner as the rail t is connected into the contact-blocks c^{22} and the rail t^x into the contact-blocks c^{19} by the conductors 43 and 45 in the intersecting track. The formation of the loops at the moment that the wheels of an engine traveling on one track enter the 110 block adjacent to the crossing-point when a train on the intersecting track is within unsafe limits, will be understood from the diagram Fig. 9.

The construction of the valve through 115 which the train-brakes are operated in such emergencies independently of the engineer's valve, is represented in Figs. 4, 5 and 6.

The piston-valve 60 controls the two ports and passages 61-62 through which the compressed air is admitted and carried to the train-pipe and also is exhausted to the atmosphere. The main outlet to the atmosphere is through the apertures 66-67; the valve 66^a is held up to its seat on the outlet 66 by a 120 125

130

coiled spring 66^b the tension of which is adjustable by a threaded nut in the usual manner. This outlet is also controlled by the piston-valve 60 through a drop-valve 65 connected by its stem to the piston-valve, and seated on the outlet by the air pressure from above.

The piston-valve is balanced in its chamber 60^x; the space above and that below the 10 diagram 63^a on the valve-stem 63 being connected through the passages *f*—*g*. The valve 70 in this passage controls the outlet 70^a to the atmosphere, from which outlet it is raised when the armature 72 is attracted to the 15 poles of the magnet *h*.

In its elevated position the piston-valve closes the pressure-inlet 61; while the air from the train-pipe finds an outlet to the atmosphere through the aperture 69 in the 20 head of the piston-valve and through the outlet 66. As often as the auxiliary valve is actuated by its magnet *h*, therefore, a direct outlet from the train-pipe to the atmosphere is set up, and the brakes are put on independently of any attention or movement on the 25 part of the engineer.

A stop-valve 73 provided with a hand-wheel for adjusting it is placed in the passage *f*—*g* for regulating the pressure on opposite 30 sides of the piston-valve.

Having thus described our invention, what we claim and desire to secure by Letters Patent is:—

1. An automatic brake-setting apparatus 35 for a railway system, comprising an electrically-operated outlet-valve on the engine auxiliary to the engineer's valve and located in the connection between the train-pipe and the source of compressed-air supply; an 40 electro-magnet for operating the outlet-valve; a battery in a local circuit, in which is included the coils of the magnet; a contact-shoe on the engine forming one terminal of the battery circuit; the other terminal being formed by the truck and wheels of the 45 engine; in combination with contact-blocks on the roadway in two series, and rails electrically isolated from each other in separate blocks, each block containing two separate 50 sets of contact-blocks one set of which is connected into one rail of the block or section next behind, and the other set into one rail of the block or section next ahead, each block or section having its rail insulated from but 55 cross-connected into the rails of the blocks or sections behind and ahead.

2. An electrically-operated outlet-valve auxiliary to the engine-valve, and having a balanced piston-valve controlling the connec-

tion between the train-pipe and the source of compressed-air supply and controlling also the communication between the train-pipe and the atmosphere; an outlet-valve controlling the communication between the atmosphere and one side of the piston-valve chamber; an 60 electro-magnet in open circuit with a local battery and operating when energized to open the outlet-valve, and means adapted to close said battery on the magnet, said means comprising track-rails electrically isolated at 65 intervals apart to divide the line into a plurality of blocks or sections, the rails of each block being cross-connected electrically with one of the rails in the blocks respectively behind and ahead, and fixed contact-blocks in 70 each block or section of track in separate sets inter-connected respectively into the remaining rails in the blocks or sections behind and ahead, whereby the rails in any block in which a train may be running will form the 75 connecting members of a metallic loop having for its remaining members one rail and one set of contact-blocks in the block or section behind and in the block or section ahead.

3. In a railway block-system a plurality of 80 metallic loops for operating electrically at points along the line electrically actuated mechanism on a train, comprising track-rails separated electrically into separate blocks or sections; conductors connecting electrically 85 beyond the points of insulation one rail of a block with one rail of the block next behind, and the remaining rail with one rail of the block next ahead; in combination with fixed contact-blocks in each block or section 90 arranged in two separate sets at intervals apart, the contact-blocks contained in one of said sets being connected into one rail of the block or section next behind, and those contained in the other set into one rail of the block or 95 section next ahead, and electrically actuated 100 brake-operating mechanism on the engine, including an electro-magnet, a battery in a normally-open circuit, one side of said battery-circuit being connected into the truck or 105 wheels of the engine, and a circuit-closing shoe connected into said battery-circuit and adapted to make contact with the contact-blocks on the roadway in the movements of the engine on the track.

In testimony that we claim the foregoing, we have hereunto subscribed our names in the presence of two witnesses.
